UNITED STATES PATENT OFFICE.

JOHN T. WEBSTER, OF YONKERS, NEW YORK, ASSIGNOR TO PAGE, WILDER & CO., OF HALLOWELL, MAINE.

DESIGN FOR A FLOOR OIL-CLOTH.

Specification forming part of Design No. 5,059, dated June 27, 1871.

To all whom it may concern:

Be it known that I, JOHN T. WEBSTER, of the village of Yonkers, in the county of Westchester and State of New York, have invented a new and original Design for Floor Oil-Cloths; and I do hereby declare that the following is a full, clear, and exact description thereof, which will enable others skilled in the art to make and use the same, reference being had to the accompanying drawings making part of this specification.

The nature of my invention is fully represented in the accompanying drawings, to which reference is made.

I claim as my invention—

The design for floor oil-cloth, as shown.

JOHN T. WEBSTER.
